COMBINED SLICING BOARD AND UTENSIL RACK

Mel Appel, Livingston, and Martin Schnur, West Orange,
N.J., assignors to Elpo Industries Inc., Fair Lawn, N.J., a corporation of New Jersey

Filed Mar. 2, 1967, Ser. No. 6,034

Term of patent 14 years

We claim:

The ornamental design for a combined slicing board and utensil rack, as shown.
